UNITED STATES PATENT OFFICE.

FRANK HOLBROOK, OF LYNN, MASSACHUSETTS; SARAH A. HOLBROOK, OF LYNN, MASSACHUSETTS, ADMINISTRATRIX OF SAID FRANK HOLBROOK, DECEASED, ASSIGNOR, BY MESNE ASSIGNMENTS, TO UNITED SHOE MACHINERY CORPORATION, OF PATERSON, NEW JERSEY, A CORPORATION OF NEW JERSEY.

HEEL-BUILDING MACHINE.

1,255,608.

Specification of Letters Patent. Patented Feb. 5, 1918.

Application filed December 6, 1911. Serial No. 664,285.

To all whom it may concern:

Be it known that I, FRANK HOLBROOK, of Lynn, in the county of Essex and State of Massachusetts, have invented certain new and useful Improvements in Heel-Building Machines, of which the following is a specification.

This invention relates to heel building machines and more particularly to machines for building heels composed of a number of lifts of leather board or other sheet material.

The object of this invention is to provide a heel building machine capable of rapidly producing heels of any of the various shapes and sizes in use in the manufacture of boots and shoes. In order to carry this object into practical effect, mechanism is provided by which the machine may be speedily adjusted to change the shape, size, and height of the heels being built.

To the accomplishment of this generally stated object and such others as may hereinafter appear, the invention comprises the features and combination of parts herein-after described and particularly pointed out in the appended claims.

Referring to the drawings:

Figure 1 is a front elevation of a heel building machine constructed in accordance with the present invention;

Fig. 2 is an enlarged detail of the heel delivering end of the machine;

Fig. 3 is a detail view of the cam lever for resetting the heel ejector;

Fig. 4 is a plan view showing two of the series of lift magazines;

Fig. 5 is a section on the line 5—5 of Fig. 4;

Fig. 6 is a section on the line 6—6 of Fig. 4;

Fig. 7 is a section on the line 7—7 of Fig. 1;

Fig. 8 is a section through the heel block carriage on the line 8—8 of Fig. 4;

Fig. 9 is a section on the line 9—9 of Fig. 8;

Fig. 10 is an enlarged rear view of a portion of Fig. 1; and

Fig. 11 is a section on the line 11—11 of Fig. 1.

The embodiment of the present invention

selected for illustration is formed of two end pieces 20 (Fig. 1) connected by a table 21 which supports a series of heel-lift magazines 22. There are but six magazines illustrated in the drawings, but this number may be increased by the addition of similar magazines to any desired number. The end pieces are also joined by a beam 23 which carries mechanism for causing a carriage supporting a heel block 24 to be reciprocated in proximity to the magazines 22. Lift delivering devices are provided which operate at the proper time to deliver one lift from each magazine to the heel block as it passes. The left end piece 20, as viewed in Fig. 1, carries mechanism for truing up the heel which has been built on the heel block, securing it in this form by any suitable means such as a nail, and finally ejecting the completed heel from the machine.

The carriage upon which the heel is built consists of the heel block 24 which is mounted to slide upon a block 25, (see Fig. 8) which, in turn, is pivotally mounted in a block 26. The block 26 is supported by a roll 27 having a seat in the block 26 and also in a block 28. The block 28 is dovetailed to engage a corresponding projection on a way 29. The way 29 is adjustably supported in an inclined position by a screw 30 (Figs. 1 and 2) at one end and a jack 31 at the other. It is apparent from Figs. 1, 2, and 8 that the heel block 24 may be adjusted about the axis of the roll 27 to bring the working surface of the heel block into a horizontal position, irrespective of the angle of the way 29. The blocks 26 and 28 may be secured in adjusted relation by the use of screws 32, 32, as is best shown in Fig. 2.

The block 28 and the carriage of which it forms a part, are constructed and arranged to slide upon the way 29. Motion is imparted to the carriage through connections with a driving shaft 33 (Figs. 1 and 11). The driving shaft is supported in bearings in two plates 34 secured to the beam 23 and, at the rear, in a bearing at the end of a projecting arm 35. A pinion 36 is fixed on the shaft 33 and in mesh with a gear 37 secured to a shaft 38. The gear 37 engages

a rack 39 attached to the lower side of a slide 40 resting upon the upper side of the beam 23 and secured against displacement by an overlaying plate 41. The slide 40 may be provided at its ends with rolls 42 (Fig. 2) supporting the slide above the beam 23 to reduce the friction therewith. The slide is connected with the carriage by means of a slotted arm 43 which engages a roll 44 mounted on a depending lug which may be formed integral with the block 28. It is apparent from Figs. 1, 2, and 11 that rotation of the driving shaft 33 will impart a sliding motion to the heel block carriage.

15 As this machine is at present constructed, it is desirable that a reciprocating motion shall be imparted to the heel block carriage. It is not essential to the spirit of the invention, however, that the heel block shall 20 reciprocate, the end to be obtained being to provide a traveling heel block and this invention comprehends any other means of returning the block to its starting position.

In order that the shaft 33 may be rotated 25 alternately in opposite directions to reverse the direction of travel of the heel block carriage, a pair of pulleys 45 (Figs. 1 and 11) are loosely mounted on the shaft and driven in opposite directions, respectively, 30 by a straight and a crossed belt. A friction wheel 46 is secured to the shaft 33 and is driven in one direction or the other in accordance with which of the pulleys it is engaged. The pulleys 45 may be moved 35 longitudinally of the shaft to engage either one with the friction wheel 46, by means of forked arms 47 which engage at one end, the hubs of the pulleys, and at the other, are secured to a slide rod 48. The end of 40 the slide rod is provided with a spool which is engaged by a fork 49, fixed on a vertical shaft 50, the upper end of which is fixed to a finger 51. The slide 40 is provided with 45 two adjustable abutments 52 and 53, one of which engages the finger 51 as the slide approaches the end of its travel in either direction, rocks the shaft 50 and, through the connections described, moves the pulleys 45 to disengage one and engage the 50 other with the friction wheel 46. It will readily be seen from Fig. 1 that the abutment 52 may be located on the slide 40 in a position to stop and reverse the motion of the heel block carriage when it is in 55 front of any one of the series of lift magazines 22.

An important feature of this invention resides in the lift delivering mechanism and in its manner of operation. The lift delivering mechanism of any one magazine is thrown into operation when the heel block is in lift receiving position with respect to that magazine. The means employed to that end are best illustrated in Figs. 4, 5, 6, 65 and 10, and as each magazine is provided

with a similar delivering mechanism, but one of these need be described.

The magazines 22 may be constructed as shown in Figs. 4 and 5, in which each side of the lifts is engaged by a member 55 secured to the table 21 and provided with an opening 56 through which the lowermost lift may be removed, and an opening 57 for the entrance of a slide 58 to eject the lift through the opposite opening. The 75 slide 58 is normally held in retracted position, with a pin 59 at one end of a slot 60, by a spring 61. The slide is actuated at the proper time by interlocking with a constantly reciprocating slide 62. This slide is 80 connected, through a standard 63, a link 64 and a lever 65 movable about a fixed pivot 66, with an eccentric strap 67. The eccentric strap embraces an eccentric 68 fast on a shaft 69 having bearings in the end 85 pieces 20 and which may be rotated by the pulley 70 and a belt 71. Power is applied to the belt by a pulley on a shaft 72 which, during the operation of the machine, is constantly driven from any suitable source 90 of power connected with the tight pulley of a pair of pulleys 73.

The slide 58 may be driven in one direction by the slide 62 by means of a latch 74 pivotally mounted on the standard 63 and 95 normally held in a substantially horizontal position, as shown in dotted lines in Fig. 6, by a spring 75. While in this position the latch reciprocates with the slide 62 in a plane above a catch 76 mounted on the slide 100 58. If the latch is turned about its pivot to the full line position while the slide 62 is in the position shown in Fig. 5, one end of the latch is engaged by the catch 76 which must then move with the latch, thereby carrying the slide 58 forward and delivering the lowermost lift in the magazine 105 through the opening 56.

The latch 74 is turned into its operative position to cause a lift to be delivered to 110 the carriage by a trip lever 77 pivoted below the table 21 at 78, (Figs. 4 and 5). The rear end of the trip lever has an upwardly projecting portion which contains a spring pressed plunger 79 adapted to engage a pin 80 in one end of the latch 74. The forward end of the trip lever has fixed therein a rod 81 the lower end of which is engaged, at times, by a cam block 82. The cam block 82 is secured to the slide 40 in 115 such relation to the heel block 24 that the trip lever 77 is operated at the time the heel block is opposite the magazine controlled by that trip.

As the slide 40 and the carriage have a 125 reciprocating motion, as has been described, it is desirable that the trip lever 77 should be actuated when the carriage is traveling in one direction only, that is, a lift should be delivered to the heel block on its work- 130

ing stroke but not on its return or idle stroke. To this end, the cam block 82 is secured to a stud 83, vertically movable in a bracket 84, and provided with a friction plunger 85. Referring now to Fig. 10, the lower end of the stud is provided with a cam finger 86 which is depressed, when the slide 40 is at one end of its stroke, by a cam plate 87 and again elevated at the other end of the stroke by a cam plate 88. Thus the cam block 82 is depressed below the ends of the rods 81 on one stroke of the slide 40 and lifted into the plane of the rod ends on the other. While the cam block 82 is in its elevated position and traveling to the left in Fig. 4, the cam surface of the block moves the rod 81 to the rear and, in order that it may be held in this position long enough to insure an operation of the slide 58, a slight dwell 820 is provided as shown in dotted lines on this figure.

It is customary to apply a coating of paste to each lift of the heel during the building operation. For this purpose there is provided a series of arms 89 (Fig. 5) projecting from a rock shaft 90 extending below the magazines 22. The ends of these arms are provided with pads 91 of felt or other absorbent material, which, when the shaft 90 is rocked, alternately dip into the paste in a paste pot 92 and contact with the lowest lift in each magazine. The table 21 is slotted at 93 (Fig. 4) so that pads can engage the lifts as described. The shaft 90 is rocked by means of a disk 94 (Figs. 1 and 5) having an eccentric pin 95 connected by a link 96 with a second eccentric pin 97 carried at the end of a shaft 98. This shaft is rotated by a belt 99 driven through a pair of speed reducing pulleys 100 and a belt 101 which is driven from the shaft 72. The location of the eccentric pins 95 and 97 to their respective axes is such that a rotation of the shaft 98 will produce an oscillation of the shaft 90. The paste is applied to the bottom of the lifts as the heel is built, therefore it is unnecessary to apply paste to the first lift used in a heel. This lift is the one taken from the magazine at the right of the series being employed to build any particular height of heel. The arms 89 are secured to the shaft 90 by means of nuts 102 in order that the arm which would apply paste to the first lift delivered to the carriage may be removed and so avoid the application of useless paste.

It has been found most convenient in the present embodiment of the invention, to turn the heel block 24 through 90 degrees after the heel is built and then to deliver the heel to a support where it is trued up to its final form, secured in this form by a nail or other fastening device, and ejected from the machine.

The required rotary motion of the heel block 24 is permitted by the pivotal connec-

tion of the block 25 with the block 26, as has been described. (Figs. 2, 4, and 8.) This connection comprises a stud 103 projecting from the block 25 passing through the block 26 and held therein by a plate 104. A gear segment 105 is fixed on the central portion of the block 25 and is adapted to be engaged by a rack 106 projecting from the left hand end piece 20 before the heel block carriage has completed its travel to the left. The result of the engagement of the rack and gear segment is to turn the carriage from the position of Fig. 4, to that shown in Fig. 2. A spring 107 connecting the block 25 and a projection from the block 26 tends to hold the heel block normally in the position of Fig. 4, with a pin 108 (Fig. 9), in the block 26, against a shoulder formed in a flange 109 on the block 25.

When the heel block has been turned to extend lengthwise of the machine, mechanism is thrown into operation to slide the block 24 on the block 25 to deliver a heel to a heel support 110. This mechanism comprises a lever 111 pivoted on the end piece 20 at 112 (Fig. 1) and provided, at its upper end, with a pin 113 which is so located that, upon rotation of the heel block, the pin 113 lies behind a pin 114 fixed on the block 24. At this time mechanism, which will be hereinafter described, is actuated to cause the lever 111 to slide the block 24 on the block 25 and against the tension of a spring 115, into the position shown in Fig. 2. The heel block 110 is indicated in broken lines in Fig. 8 in proper relation to the block 24 when it is advanced as above described, the other parts of this figure being temporarily disregarded. The spring 115 tends to retain the blocks 24 and 25 in the relative position shown in Fig. 8, with a pin 116 at the end of a slot 117 in the block 24.

The heel support 110 is preferably made of sheet metal having its projecting end bent slightly downward so as to lift the heel 110 somewhat above the surface of the heel block as it is forced on to the support. The heel support is carried by a slide 118 vertically adjustable, by the manipulation of a screw 120, in a slot 119 in the end piece 20. A heel breast plate 121 extends above the support 110 with its lower end held loosely between the support and a projection of the slide 118. A hand nut 122 having a screw threaded connection with lugs 123 on the plate, provides means for varying the angle of the plate with the heel support and thus determining the slant of the breast of the finished heel.

One of the important features of this invention relates to the means by which the heels are given the desired contour and by which this contour may be conveniently varied in accordance with the variation in the shape of the finished heel. Guides are pro-

vided to approximately determine the relation of each lift with the previous lift delivered to the heel block. The guides are adjustable to accommodate heels of varying sizes and also adjustable to conform to the angle or taper of the heel from top to bottom.

A guide 124, (Figs. 2, 4, and 8) to determine the slant on the back of the heel, is pivoted at its lower end to a bar 125 adjustably secured, by a bolt 126, in a slot to the heel block 24. The angle of the guide 124 may be varied from a perpendicular position, such as would be required for a military heel, to as great an angle as may be desired on ladies' high heels, by adjusting a screw 127 in an upright 128 projecting from the bar 125. A spring 129 holds the guide against the screw as is most clearly shown in Fig. 8. Two guides 130 are provided for the sides of the heel. These guides are pivotally connected with two arms 131 loosely secured to the block 24 by screws 132. Adjusting screws 133, carried by uprights 134 fixed to the arms 131, are employed to vary the angle of the guides 130 in the same manner as has been described in connection with the guide 124. The guides, as will be apparent, define a heel-shaped space or recess 30 and, with the block, constitute a heel form to which the lifts are delivered, and in which they are assembled in the shape of a heel. When it is desired to change the side guides to accommodate a wider or narrower heel, the arms 131 are turned about the screws 132 by means of screws 135 carried in straps 136 fixed to the heel block. Springs 137 extending from the straps 136 to projections on the arms, hold the arms separated 40 and against the screws 135.

The normal adjustment of the side guides 130 is such that there is a slight clearance on each side of a centrally positioned lift, thus allowing the possibility of irregularity 45 in the vertical outline of the heel. The lifts are correctly positioned, or the heel is trued up, by pressure of the guides 130 upon the sides of the heel and the pressure at the back and at the breast of the heel, between the guide 124 and the plate 121. The side guides are forced toward each other and against the heel during the last part of the sliding movement of the heel block 24 under the impulse of the lever 111. The ends 50 of the arms 131 are beveled at 138 (Fig. 4) to afford a cam action when the beveled portions engage two screws 139 threaded into straps 140 secured to the end piece 20. The sliding movement of the heel block also 55 presses the heel against the breast plate 121 by the force of the guide 124 at the back of the heel. The manner in which the heel is trued up is best illustrated in Fig. 2 and Fig. 8 in which the heel support 110 and 60 the breast plate 121 are shown in heel re-

ceiving position only to the block 24. By reference to these figures it is apparent that the edge of each heel is firmly pressed in four directions and thereby uniformity of the heels produced is assured. It will be 70 apparent to one skilled in the manufacture of heels that the heel engaging surface of the guide 124, or of any of the guides, need not necessarily be a straight line from top to bottom but may be curved if desired so 75 as to leave less stock to be trimmed off on a heel having a curved taper, such, for instance, as a "Louis" heel.

It is desirable that the lifts should be securely fastened together before the heel is ejected from the machine and this is preferably accomplished by driving a nail through the heel. As illustrated in Fig. 1, a raceway 142, which may be of any suitable form, provides nails, from any convenient source of supply, to a driver 143. The driver is adjustably mounted in a slide block 144 which is carried in a continuation of the slot 119, to which reference has been made. (See Fig. 7.) A foot 145 carried on the lower end of a spring supported plunger 146 is provided to clamp the heel upon the heel support 110 while the nail is being driven. The plunger 146 has a bearing in a bracket 147 secured to the end piece 20 and it is thrust downward upon the heel by a bar 148 carried in a way in the slide block 144 and held yieldingly downward by a heavy spring 149. The slide block 144 is joined by a connecting rod 150 with an eccentrically mounted pin 151 in a disk 152 having a bearing in the end piece 20. The disk 152 is rotatable with the driven member of a clutch 153 which also carries a cam 154 to actuate the lever 111 which has been 105 described.

The clutch 153 is driven by the shaft 72 and may be of any of the well known forms for turning the driven member through one revolution, but, for the purpose of illustration, it has been shown as having a plunger 155 which is engaged with the driven member by the movement of the lever 156. The clutch is rendered operative by the heel block carriage as it reaches the end of its travel toward the heel delivering end of the machine, that is, to the right in Fig. 10. As the slide 40 comes to this position, a stud 157, carried on a strap 158 secured to the slide, contacts with the upper end of a lever 159, the lower end of which (see Fig. 1) is connected by a link 160 with the lever 156. By this construction the clutch 153 is rendered operative to slide the heel block 24 on the block 25 and, by proper timing of the cam 154, then to drive the nail. The lever 111, being at once retracted by a spring 161, allows the heel block to return to its normal position under the stress of the spring 115, leaving the completed heel on 130

the support 110 ready to be ejected from the machine.

The ejecting devices, as at present employed, comprise a rod 162 (Fig. 7) adjustably secured to a lever 163 pivoted on the end piece 20. The lower end of the lever is held to the left, under the impulse of a spring 164, so far as it is permitted to go by a latch 165 which engages the upper end 10 of the lever. A rod 166 connects one end of the latch 165 with a lever 167 (Fig. 10) pivoted at 168 on the beam 23. The other end of this lever carries a trip 169 which is free to swing in one direction but is stopped 15 in the other direction by a pin 170. The stud 157, hereinbefore described, has an extending end 171 of reduced diameter. As the slide 40, and, perforce, the heel block carriage, travels to the right in Fig. 10, the trip 169 swings to allow the pin 171 to pass, but on the return of the pin the angular lower surface of the trip causes the end of the lever 167 to rise thereby pulling down the rod 166 and releasing the upper end of 20 the lever 163 from the latch 165. The lower end of the lever then swings sharply to the left by the action of the spring 164 and the rod 162 strikes the heel and throws it from the machine.

36 The ejector is reset by the continued movement of the slide 40 on its idle or return stroke. The lower end of the lever 163 is connected by a link 172 with a post 173 rising from the end of a cam lever 174 mounted on a bracket on the front of the beam 23. The slide 40 carries a depending lug 175 which engages the cam end of the lever 174 and thereby swings the lever 163 to its original position where it is retained 40 by the latch 165 until another heel is to be ejected. Fig. 3 shows the lever 174 in dotted lines in the position it occupies directly after the heel has been ejected and in full lines in the position to which it is returned by 45 the lug 175 in its travel to the right.

In order that the manner and facility of adapting this machine to building heels of a different size, height, and shape may be clearly understood, it will now be assumed 50 that it is desired to adjust the machine to build heels of only five lifts, that is, what is known as a $\frac{1}{2}$ heel. The first operation is to throw the driving pulleys 45 into neutral position, by means of a handle 176 after 55 which the heel block carriage may be moved by the hand wheel 177. The hand wheel is now turned to bring the heel block 24 into line with the fifth lift magazine, counting from the left in Fig. 1. The abutment 52 is moved to a position in contact with the finger 51 and the cam plate 88 (Fig. 10) is moved into engagement with the stud 83. These adjustments will, when the machine 60 is started, cause the cam block 82 to be lifted into the plane of the rods 81 and the

carriage to reverse its direction of travel at the proper time. The surface of the heel block 24 is now found to be below the level of the bottom lift in the magazine in juxtaposition thereto, so the jack 31 is manipulated to raise the upper end of the way 29 until the surface of the heel block is but very slightly below the table 21. This adjustment will, however, have produced an error in the relation of the heel block and 70 the lift in the last magazine to the left when the block is in receiving position thereto. This is corrected by adjusting the screw 30. The guides 130 and the guide 124 are now adjusted to correspond to the shape and 75 size of the heel to be built, in a manner which is plain from the foregoing description. The heel support 110 is adjusted by the screw 120 to bring its level slightly above that of the heel block at the end of its working 80 stroke and such minor adjustments as may be necessary are made to the nail driver and the ejector. The pasting arm 89 (Fig. 5) for the fifth magazine is then removed 85 and the machine is ready to operate. 90

In the operation of this machine, the heel block 24 starts its working stroke from a point slightly to the right of the first magazine from which a lift is to be taken which, as is illustrated in Fig. 1, would be the sixth 95 magazine. As the cam block 82 engages the first rod 81, a lift is delivered to the heel block, as has been described. Lifts are delivered from successive magazines in the same way. It will be observed that, as the 100 carriage travels, the gradually increasing distance from the top of the heel block to the level of the table 21 will compensate for the increase in the height of the heel being built so that the top of the partly formed heel is always at the right height to receive the next lift. The pasting arms 89 which are continuously operating, will keep the bottom lift in each magazine, except the sixth, which will be the bottom lift on the 105 heel block, well supplied with fresh paste. After passing the series of magazines, the heel block is turned by the rack 106 and the gear segment 105, the clutch 153 is thrown into operation and the cam block 82 is depressed. The heel block 24 then slides forward by reason of the lever 111 and delivers the heel to the heel support 110 at the same time truing up the heel by the pressure of the plate on the heel breast and guides at 115 the sides and back. The heel block carriage at once starts to return, its direction of travel being reversed by the abutment 53 engaging the finger 51. The heel is nailed and ejected during the first part of the return stroke of the carriage, the ejector is reset, as has been described, and finally the cam block 82 is elevated, the abutment 52 actuates the finger 51 and the carriage starts 120 another working stroke. 125

It will be observed that the form of the heel produced by this machine, can be very easily varied. It will be necessary, of course, to fill the magazines with lifts of proper sizes 5 to produce the desired taper of the heel from top to bottom, but without changing the sizes of the lifts in the magazines, it is possible to vary the angle of the heel at the breast and at the back of the heel. By 10 means of these adjusting devices a great saving in material is effected. Instead of producing heels of a standard shape and size and then trimming the heel to one of several finished forms, the contour of the rough 15 heel can be easily varied so as to produce a rough heel for each of the finished forms, on which the minimum amount of trimming is required.

It is to be distinctly understood that, 20 while this invention has been illustrated and described in the best form at present known to the inventor, the construction and arrangement of parts herein set forth is not essential to the invention and the true scope 25 of the invention is not limited thereby, except in so far as it is specified and definitely set forth in the claims.

What is claimed as new, is:—

1. A heel building machine, having, in 30 combination, a heel block, a series of lift magazines, means for producing a relative longitudinal movement between the heel block and the lift magazines, means for delivering lifts from successive magazines 35 to the heel block, and means for uniformly varying the distance from the plane of the lift delivering means to the plane of the lift receiving surface of the heel block during the interval between successive operations of 40 the lift delivering means.

2. A heel building machine, having, in combination, a carriage, a series of lift magazines, a way upon which the carriage travels, 45 means for delivering lifts from the magazines to the carriage, and means for varying the angle between the way and the series of magazines.

3. A heel building machine, having, in combination, a carriage, a series of lift magazines, means for causing the carriage to travel 50 in a path at an angle to the general plane of the lift delivering ends of the series of magazines, and means for delivering lifts from successive magazines to the carriage 55 as it arrives in lift receiving position with respect to each magazine.

4. A heel building machine, having, in combination, a carriage, a series of lift magazines, means for causing the carriage to 60 travel in a path at an angle to the general plane of the lift delivering ends of the series of magazines, means for varying the angle of the path of travel of the carriage, and means for delivering lifts from successive 65 magazines to the carriage as it arrives in lift receiving position with respect to each magazine.

rives in lift receiving position with respect to each magazine.

5. A heel building machine, having, in combination, a carriage, a series of lift magazines, means for causing the carriage to travel 70 in a path at an angle to the general plane of the lift delivering ends of the series of magazines, means to permit relative adjustment between the plane of the lift delivering ends of the magazines and the path of travel of the carriage, and means for delivering lifts from successive magazines to the carriage as it arrives in lift receiving position with respect to each magazine. 80

6. A heel building machine, having in combination, a heel block, a series of lift magazines, means for delivering lifts from the magazines to the heel block, guides on the heel block to approximately position the lifts as they are delivered, and means for closing the guides upon the heel to correct the alinement of the lifts. 85

7. A heel building machine, having, in combination, a heel block, a series of lift magazines, means for delivering lifts from the magazines to the heel block, a guide on the heel block to approximately determine the shape of the back of the heel, a plate to engage the heel breast, means for pressing the heel between the plate and the guide, 95 to give the heel its final contour, and means for permanently securing the lifts together.

8. A heel building machine, having, in combination, a series of lift magazines, a heel block, means for delivering lifts from the magazines to the heel block, an angularly adjustable plate to engage the heel breast, and means for forming the breast of the loose heel by engagement of the plate 100 after it is delivered to the heel block. 105

9. A heel building machine, having, in combination, a heel block, a series of lift magazines, means for delivering lifts from the magazines to the heel block, guides on the heel block to determine the contour of the heel being built, and means for adjusting the guides to vary the contour of the heel. 110

10. A heel building machine, having, in combination, a heel block, a series of lift magazines, means for delivering lifts from the magazines to the heel block, guides on the heel block to determine the approximate contour of the heel being built, means for adjusting the guides to vary the contour of the heel, and means for closing the guides upon the heel to give the lifts the proper relation to form a heel of the desired contour. 115

11. A heel building machine having, in combination, a series of lift magazines, a traveling heel block, independent power actuated mechanism for delivering lifts from the magazines to the heel block, and connections between said mechanism and the heel block for throwing the delivering mechanism. 125 130

nism into operation in timed relation to the travel of the block.

12. A heel building machine, having, in combination, a carriage, a series of lift magazines, a way in proximity to the magazines upon which the carriage travels, means controlled by the carriage for delivering a lift from each magazine to the carriage as it passes, a heel support to receive the heel collected by the carriage, a plate to engage the breast of the heel upon the heel support, means for pressing the heel against the breast plate to determine the angle of the breast of the heel, and means for securing the lifts permanently together.

13. A heel building machine, having, in combination, a traveling carriage, a series of lift magazines, means rendered operative by the carriage for delivering a lift from each magazine to the carriage as it passes, a heel support, means for delivering the loose heel formed on the carriage to the heel support, adjustable means for giving the heel a predetermined form after it is delivered to the heel support, and means for permanently securing the heel in this form.

14. A heel building machine, having, in combination, a carriage, a heel block on the carriage, a way upon which the carriage travels, means for delivering lifts to the heel block, and means for adjusting the angle of the heel block with respect to the carriage.

15. A heel building machine, having, in combination, a carriage, a series of lift magazines, an adjustable way in proximity to the series of lift magazines upon which the carriage reciprocates, means for delivering lifts from the magazines to the carriage, means for actuating the lift delivering means as the carriage approaches each magazine, and means for varying the length of the path of travel of the carriage.

16. A heel building machine, having, in combination, a carriage, a heel block carried by the carriage, a series of lift magazines, means for delivering lifts from the magazines to the heel block, a heel support, and means for sliding the heel block on the carriage to deliver the heel collected thereon to the heel support.

17. A heel building machine, having, in combination, a carriage, a series of lift magazines, means for delivering lifts from each magazine to the carriage, an adjustable inclined way upon which the carriage travels, a heel nailing device, and means connected with the carriage for causing the lift delivering means and the nailing device to operate when the carriage is in working relation with the lift delivering means and the nailing device, respectively.

18. A heel building machine, having, in combination, a carriage, a series of lift magazines, a way in proximity to the magazines, means for causing the carriage to travel al-

ternately in opposite directions on the way, means for delivering lifts from the magazines to the carriage, and means for rendering the lift delivering means operative during the travel of the carriage in one direction.

19. A heel building machine, having, in combination, a carriage, a series of lift magazines, means for applying paste to the bottom lift in each magazine, and means for projecting the bottom lift from each magazine edgewise onto the carriage to form a heel.

20. A heel building machine, having, in combination, a heel block, a series of lift magazines, means for producing a continuous relative longitudinal movement between the heel block and the lift magazines, means for producing a continuous relative vertical movement between the heel block and the series of lift magazines, and means for delivering lifts from the magazines to the heel block.

21. A heel building machine, having, in combination, a carriage, a series of lift magazines, means for applying paste to the bottom lift in a predetermined number of the magazines, and means for delivering the bottom lift from each magazine to the carriage.

22. A heel block having a plurality of guides to engage points on the periphery of the heel, means for angularly adjusting the guides to conform to the taper of the heel, and separate means for bodily adjusting the guides to conform to the size of the heel.

23. A heel building machine having a carriage mounted for movement in a generally horizontal direction, a heel block on the carriage, means for building the heel on said block, and means for adjusting in a vertical plane the angular relation of the heel block and the carriage.

24. A heel building machine having a carriage, a heel block on the carriage, means for building a heel on the block, and means for imparting a rotary movement to the heel block after the heel is built, to position the heel for subsequent operations.

25. A heel building machine having, in combination, a lift assembling device, a series of lift magazines, means for producing relative longitudinal movement between the assembling device and the lift magazines, means for delivering lifts from the magazines to the assembling device, and means for uniformly varying the distance from the plane of the lift delivering means to the plane of the bottom lift of the heel being assembled during the interval between the engagement of successive lifts by the assembling device.

26. A heel building machine having, in combination, a lift assembling device, a series of lift magazines, means for causing the assembling device to travel in a path

at an angle to the general plane of the lift delivering ends of the series of magazines, and means for delivering lifts from the magazines into position to be successively 5 engaged by the assembling device as it arrives in lift engaging position with relation to each magazine.

27. A heel building machine having, in combination, a series of lift magazines, a 10 traveling lift assembling device, independent power actuated mechanism for delivering lifts from the magazines to the assembling device, and connections between said mechanism and said device for throwing 15 the delivering mechanism into operation in timed relation to the travel of the assembling device.

28. A heel building machine having, in combination, a traveling heel block, means 20 for delivering lifts to the heel block at a series of lift receiving stations, and means for correcting the alinement of the stack of lifts on the heel block at a subsequent station.

25 29. A heel building machine having, in combination, a heel block, means for delivering a series of lifts successively to the heel block to build up the heel, means for alining said lifts on said heel block, nailing mechanism, and means for delivering the alined lifts on the heel block to the nailing mechanism.

30. A heel building machine having, in combination, a heel block, a series of lift 35 magazines, means for causing the heel block to travel in proximity to the magazines, and a heel engaging plate arranged in the path of travel of the heel block to aline the heel lifts on said heel block as delivered from 40 said magazines.

31. In a heel building machine, the combination of mechanism comprising a series of lift delivering devices, a member including a heel block, means to permit a relative 45 movement between the series of lift delivering devices and the heel block, and means to permit adjustment of the angular direction of such relative movement between said mechanism and said member.

50 32. In a heel-making machine, a row of supports for holding a series of cemented heel lifts in correspondingly disposed positions, a heel-holder at one end of said row of supports, means to collect said lifts in a pile 55 and deliver them onto said holder, and a clamping device for clamping the lifts on the holder after they have been delivered thereto.

33. In a heel-making machine, a row of 60 supports for holding a series of cemented heel-lifts in correspondingly disposed positions, a heel-holder at one end of said row of supports, a heel-clamping device for said holder, assembling-means movable to collect 65 said lifts in a pile from said supports and to

deliver them in heel form onto said holder, and means to move said clamping device into clamping engagement with the assembled lifts while held by said assembling-means on said holder.

70 34. In a heel-making machine, a heel-holder having a clamping device, a heel-forming device movable to said heel-holder to deliver an assembled heel thereto, and means for automatically operating said 75 clamping device as the heel is delivered to the holder by the forming device.

35. In a heel-making machine, a heel-holder having a heel-receiving face, a heel-forming abutment mounted at one side of 80 said face, a clamping device arranged to clamp an assembled heel on said face, a heel-forming member movable to deliver the assembled lifts onto said face, against said abutment, and means for automatically operating said clamping device to clamp the lifts on said face as they are delivered thereto and held in heel form against said abutment by said member.

90 36. In a heel-building machine, in combination with a support for lifts and a holder for receiving heel-blanks, a carrier adapted to be rocked and reciprocated and having a heel-former mounted thereon and adapted to be moved alternately to positions opposite 95 said support and said holder.

37. In a heel-building machine, in combination with a support for lifts, a pasting device mounted in said support, a holder for receiving heel-blanks, and a carrier having 100 a heel-former mounted thereon and adapted to be moved alternately to positions opposite said support and said holder.

105 38. In a heel-building machine, in combination with a support for lifts, a pasting device mounted in said support, a holder for receiving heel-blanks, and a carrier having a heel-former mounted thereon and adapted to be moved alternately to positions opposite 110 and in line with said pasting device and opposite and in line with said holder.

115 39. In a heel-building machine, in combination with a support for lifts and a holder for receiving heel-blanks, a blank carrier adapted to be rocked in a horizontal plane and reciprocated and adapted to be moved alternately to positions opposite said support and said holder.

120 40. In a heel-building machine, a heel clamp, a heel-form movable from a lift receiving position to a position directly over one member of the clamp, means to move the other member of the clamp to clamp the assembled heel thus held by said form, and 125 means permitting a side of the form to yield to permit disengagement thereof from the heel as the form is withdrawn from its position over the clamp while the heel remains clamped.

41. In a heel making machine, the combination of a heel holder having a clamping device, a form in which lifts may be assembled in the shape of a heel, the said form being movable to the holder to deliver an assembled heel to the clamping device, and means for automatically operating said clamping device as the heel is delivered to it.
- 5 42. In a heel building machine, a heel holder having a horizontally disposed heel support, a clamping device movable into engagement with a heel upon the support, a heel-form having a heel receiving recess 15 therein movable to a delivering position in which an assembled heel in the form is directly over the heel support, the form being provided with means for engaging the edges of the lifts assembled therein, means for 20 actuating the clamping device to clamp a heel while held by the form in said delivering position, and means permitting said lift edge engaging means to separate to permit the form to be withdrawn from the heel, 25 leaving the heel upon the heel support.

43. A heel building machine having, in

combination, means for supporting a series of lifts, a traveling lift collecting device, independent mechanical means for delivering lifts from the supporting means to the collecting device, and connections between said delivering means and the collecting device for throwing the delivering means into operation in timed relation to the travel of the collecting device.

35

44. In a heel-building machine, a heel clamp having a horizontally disposed member, and a heel-form reciprocally movable between a filling position and a delivering position directly over said member, and having a heel-forming recess therein opening toward said delivering position and heel-engaging fingers mounted at opposite sides of said recess, said fingers being yieldable to permit the withdrawal of the form from the heel, while the heel is held by the heel clamp.
